UNITED STATES PATENT OFFICE.

HANS HONIGMANN, OF DULUTH, MINNESOTA.

AUTOMATIC SHEET-REGISTERING DEVICE FOR PLATEN PRINTING-PRESSES.

1,174,725.

Specification of Letters Patent. Patented Mar. 7, 1916.

Application filed April 9, 1914. Serial No. 830,725.

To all whom it may concern:

Be it known that I, HANS HONIGMANN, a citizen of the United States, residing at Duluth, in the county of St. Louis and State of Minnesota, have invented certain new and useful Improvements in Automatic Sheet-Registering Devices for Platen Printing-Presses, of which the following is a specification, reference being had therein to the

accompanying drawing.

My invention relates to improvements in automatic sheet registering devices for platen printing presses.

The object of my invention is to provide an automatic sheet registering device for platen printing presses, connected to and operated by the press simultaneously with each operation of the press.

Another object is to provide a registering device of this character capable of adjustment to all requirements of the press and of a character simple in construction and effective in operation.

In the accompanying drawings, Figure 1 is a top or plan view of a printing press platen with my improved registering device attached thereto. Fig. 2 is a side elevation of the same. Fig. 3 illustrates the actuating mechanism of my device with the band spring in vertical elevation. Fig. 4 is an enlarged perspective view showing in detail a portion of my registering device. Fig. 5 is a top or plan view of one end portion of my device. Fig. 6 is another plan or top view of the opposite end portion of my device. Fig. 7 is a sectional view taken along the line A—B, Fig. 6.

Referring now to the drawings, 1 represents a shaft as found upon a platen printing press, upon which is mounted the oscillating platen 2, common to such presses.

3 represents one of the inking roller carriage rods which co-operates with the platen 2 and is indirectly connected to the shaft 1 thereof in a manner to suitably operate the inking rollers, as is common in all platen printing presses.

4 represents a metal spring attached to the frame 5 of the machine by means of the bolt 6, and is adjustable thereon by means of the slot 7, through which the bolt passes. It is understood that any other suitable means may be employed in the place of the spring 4 without departing from my invention. This spring 4 extends from its point of attachment at the bolt 6 upwardly and in such curvilinear form as to be most suit-

able for the requirements of my device and forms one of the actuating members of the same. At its upper end is the bent out portion 4' which impinges the roller carriage rod 3 in such a manner that the spring is thrust forward and backward alternately by the vertical motion of the rod 3.

9 and 10 represent the gripper finger bar supports, attached one at each end of the lower edge of the platen 2, and in which the gripper finger bar 11 is pivotally mounted in such a manner and with suitable attachments, not forming part of this invention, for raising and lowering the gripper fingers 12—12 as the platen is rocked backward and forward, this manner of operating the gripper fingers being common to such presses and not forming any part of my present invention. The spring 13, attached to the lowermost portion of the bar 11, holds the gripper fingers, normally, in a withdrawn position.

14 represents a shaft extending parallel with and between the bar 11 and the platen 2 and is journaled within the supports 9 and 10 and forms the pivotal supports of the bar 11, this shaft being susceptible of longitudinal reciprocation independent of the bar, and projecting sufficiently at one end to engage the spring 4 by means of the roller 15, pivoted within the socket 16 attached to the end of the shaft 14. About the shaft 14, adjacent the pivotal support 10, is mounted the spiral spring 18 compressed intermediate the end bearing of the bar 11 and the collar 17, whereby the opposite end of the said shaft 14 is maintained normally in an extended position.

19 represents the flat metal arm of the registering device, having at its free end the projecting tapering finger 20. At its opposite end the arm 19 is attached to a sliding sleeve 21 upon the shaft 14 and is surmounted by the flat metallic spring 22, the latter spring and the arm 19 being attached to the sleeve 21 by means of the screws or rivets 30. In this device the flat spring 22 forms the adjusting means by virtue of the pin 23 mounted upon its free end and the transverse slots or grooves 24 within the upper surface of the shaft 14. By this means any desired adjustment longitudinal the shaft 14 may be maintained regardless of the slight rotation which may be transmitted the shaft 14, as hereinafter shown. The arm 19 and its members are held flat upon the platen 2 by means of the spiral spring 25, one of

whose ends is secured to the sleeve 21 while the other end 25' is projected beneath the platen 2, or may be secured in any other desired manner to arrive at the desired results. Upon the arm 19 is suitably, pivotally mounted a metal rod 26 longitudinal with the same and whose outer end is bent to form the clip finger 27 correspondent with the finger 20 and normally held tightly upon the upper surface of the latter by means of the spring 28. At the opposite or actuating end of the rod 26 the end is bent at right-angles parallel with the finger 27 and again at right angles parallel with the principal part of the rod 26, forming the crank arm 29 projecting over the edge of the platen above the shaft 14.

Adjacent the sleeve 21, mounted upon the shaft 14 between the said sleeve 21 and the collar 31 is the slidable trigger 32 provided with the pin 33 whereby the trigger maintains a constant position upon the peripheral surface of the shaft 14 by means of a groove 34 wherein is inserted the pin 33, thus allowing of a sliding motion longitudinal the shaft 14 as the registering arm 19 is moved backward or forward upon the shaft 14 for the purpose of adjustment. A metal strap 35 is provided whereby the sleeve 21 and the collar 31 are maintained in correct relative position regarding each other, in order that the various parts of the registering mechanism may be adjusted as a unit.

At the end of the shaft 14, opposite that impinging on the spring 4, the same being projected beyond the pivotal gripper finger bar support 10 wherein it is journaled, and capable of free motion longitudinally, is pivotally mounted a tripping member comprising a suitable arm 36 so bent as to engage with the gripper finger bar 11, and having an equalizing weight 37 to insure the proper action of the tripping member, as hereinafter shown. To assist the action of this member I have also beveled a portion of the edge of the gripper finger bar, as illustrated at 38, in such a manner that the arm 36, when bearing upon that portion of the bar 11, will slip off and assume a position behind the same.

The shaft 14, being attached to the platen 2 and the gripper arm 11, descends with the same, the roller 15 bearing against the spring 4 by means of the pressure of the spring 18 and describing the arc A-B upon the same, as indicated in Figs. 2 and 3. From the manner of its attachment and construction the arm 19, with its members 20, 21, 26, etc., will move backward and forward with the like motion of the shaft 14, as actuated by the spring 4, or as it follows the peculiar shape of the same, since, in cross section, the spring 4 bends outwardly from A to B, admitting of the shaft, in its descent to project in that direction, drawing

the registering apparatus with it. The spring 4, in cross-section, also having the bent out portion 4' at its upper extremity, wherewith it engages the rod 3 on the latter's upward stroke in such a manner as to thrust the spring 4 toward the platen, resulting in a like motion in the registering device through engagement with the end of the shaft 14.

In the course of operation of this type of printing presses the platen is at nearly a horizontal position when receiving a sheet and revolves through an arc of a circle to nearly a vertical position when printing, during which arc the gripper finger bar 11, by means of cams, not shown, assumes a position flush with the platen. By so doing the gripper fingers 12-12 perform their function of holding the sheet in place for printing. As is common in this manner of printing presses the rod 3 rises as the lower edge of the platen begins to descend. Thus, with my device attached thereto, the shaft 14 and the roller 15 will be at the position shown at A upon the spring 4 when the lower edge of the platen begins to descend. Also the rod 3, in its upward motion, will impinge upon the inclined portion 4' of the spring 4 and thus, through engagement with the shaft 14, produce a like action upon the registering members. Thus it will be seen that when the platen is receiving a sheet for printing the roller 15 mounted upon the shaft 14 will be rising to the point A upon the spring 4 and the bent out portion 4' of the spring 4 will impinge the side of the rod 3. Therefore the shaft 14 will be approaching its most extreme distance from the rod 3 and, as a consequence, the arm 19 and the co-respondent rod 26 will be approaching the sheet to be printed with the fingers 20 and 27 distended. At the culmination of this motion, which is timed to occur at the exact moment the sheet is to be printed, indicated as 39 in Figs. 1 and 4, is placed upon the platen by the feeding device, not shown, the roller 15, and consequently the shaft 14 and its depending members, will have reached the extreme point of reciprocal motion, at which point the other extremity of the shaft will have thrust the tripping member 36 from below the gripper bar 11, thus allowing the shaft 14 to revolve sufficiently upon its axis, by reason of the twisting motion imparted by the spring 18, which is also assisted by the weight 37, to allow the trigger 32 to fall upon the surface of the platen, thus releasing the crank arm 29 and consequently the finger 27 impinges the sheet 39 between the same and the finger 20. As has been said the rod 3 descends as the lower edge of the platen rises. Therefore, at the position noted above, the rod will descend to its lowest point as the sheet to be printed is seized

by the fingers 20 and 27. At this point the bent out portion 4' of the spring 4 will slip over the rod, allowing the shaft and the component parts of the arm 19 to withdraw 5 the sheet, drawing it toward the tympan pins 40, which determine the proper point of register, as is customary. The sheet being now received the platen descends, the shaft 14 following horizontally the course of the 10 roller 15 from A to B upon the spring 4, which spring, as has been shown, is bent outwardly from A to B. Thus, the sheet continues to be withdrawn until it assumes its proper position in close contact with the 15 tympan pins 40, as the roller 15 progresses outwardly from A to B, just as the rod 3 is rising until the end portion 4' of the spring 4 again impinges the side of the rod 3. At the bottom of the arc the platen 20 assumes nearly a vertical position and, as has been said, the gripper bar 11 takes a position flush with the same. In so doing the bell crank arm 36 of the tripper member will have dropped behind the gripper 25 bar 11. In this position the sheet 39 is printed. The lower edge of the platen then begins to ascend. In doing so the gripper bar retains the bell crank arm 36 so that the shaft 14 is so twisted as to elevate the 30 trigger 32 from the surface of the platen, at the same time raising and retaining in an elevated position the crank arm 29 and the finger 27, releasing the sheet. The fingers of the registering apparatus are now open 35 and move forward with the arm 19 and rod 26 as the shaft 14 and roller 15 rises to the position shown as A, and move backward as the descending rod 3 allows the bent out portion 4' of the spring 4 to project over 40 the same, as shown in Fig. 3. In this position the sheet is removed and a new one supplied and the process is repeated as already described. It will thus be seen that with each repetition of the above operation 45 a like action will result, wherewith a perfect registering of the sheets may be obtained.

Having thus described my invention what I claim and desire to secure by Letters Patent is:

1. The combination with a platen printing press of a reciprocally actuated shaft pivotally mounted upon the lowermost edge of the platen a crank arm carried by the 50 shaft, an arm pivotally mounted upon the shaft and resting upon the platen, a sheet engaging rod pivotally carried by the arm and actuated by the crank arm mounted upon the shaft, whereby the sheet may be engaged or disengaged by the rod, and fed to and removed from the platen by the reciprocal motion of the shaft.

2. In an automatic sheet registering device of the character described, comprising a press having a pivotally operated platen, 65 a gripper bar pivotally mounted upon the platen, a shaft journaled intermediate the gripper bar and platen and upon which the former is carried, means for reciprocally actuating the shaft, sheet engaging means 70 pivotally mounted upon the shaft and resting upon the face of the platen whereby the sheet is fed to and removed from the platen by the reciprocal motion of the shaft.

3. In an automatic sheet registering device of the character described, comprising a press having a pivotally operated platen, a gripper bar pivotally mounted upon the platen, a shaft journaled intermediate the gripper bar and platen and upon which the 80 former is carried, means for reciprocally actuating the shaft and operated by working parts of the press, means for conveying the reciprocal motion to a sheet engaging means upon the surface of the platen. 85

4. In an automatic sheet registering device of the character described the combination of a sheet engaging means resting upon the platen and composed of opposing members for engagement with a sheet to be 90 printed, a shaft journaled upon the platen and actuated to move longitudinally and to partially rotate by means operated by working parts of the press, a trigger member mounted upon the shaft in direct engagement with the sheet engaging means, means for operating the trigger member whereby the opposing members of the sheet engaging means may be distended for the release and 95 reception of a sheet, or released for impingement upon the sheet to be printed. 100

5. In an automatic sheet registering device of the character described, the combination of a sheet engaging means resting upon the platen and composed of opposing members for engagement with a sheet to be 105 printed, a shaft journaled upon the platen and oscillated by means operated by the working parts of the press, a trigger member mounted upon the shaft in direct engagement with the sheet engaging means, means for operating the trigger member whereby the opposing members of the sheet 110 engaging members may be distended for releasing and reception of a sheet, or released for impingement upon the sheet to be 115 printed.

In testimony whereof I hereunto affix my signature in the presence of two witnesses.

HANS HONIGMANN.
